UNITED STATES PATENT OFFICE

2,492,325

GARMENT HANGER

Frederick P. Schroeder, Scranton, Pa.

Application July 9, 1947, Serial No. 759,758

2 Claims. (Cl. 211—100)

I

This invention relates to new and useful improvements in garment hangers and the primary object of the present invention is to provide a collapsible hanger that is quickly and readily applied to a supporting structure to engage and support a plurality of trousers, skirts, and the like.

Another important object of the present invention is to provide a hanger including a plurality of spaced parallel arms so designed as to permit trousers or the like to be conveniently inserted between adjacent arms to be supported therefrom without in any way wrinkling or harming the trousers applied thereto.

A further object of the present invention is to provide a hanger including novel and improved means for retaining the garment supporting arms in a raised position.

A still further aim of the present invention is to provide a garment hanger that is simple and practical in construction, neat and attractive in appearance, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the present invention;

Figure 2 is a fragmentary side elevational view showing the present invention applied to a supporting surface with parts thereof broken away and shown in section, and with dotted lines showing the position of the garment supporting arms in a lowered position; and

Figure 3 is a fragmentary front elevational view showing the lower corner of the base member.

Referring now to the drawings in detail, wherein, for the purpose of illustration, there is disclosed a preferred embodiment of the present invention, the numeral 10 represents a preferably flat base member substantially polygonal in form which is provided with apertures 12 engaging suitable fastening means for attaching the same in a preferably vertical position against a supporting surface such as a wall, door or the like 14.

Projecting outwardly from opposite sides of member 10 near the upper end thereof is a pair of spaced parallel ears or fulcrums 16 between

which there is journaled a pivot pin 18. Fixedly mounted on the pin 18 are the ends of a plurality of spaced parallel arms 20. Spacer blocks 22 fixedly mounted on the pin 18 extend between adjacent arms to retain the arms in an evenly spaced position.

The numeral 24 represents a substantially U-shaped arm supporting bracket having its terminal ends turned inwardly to pivotally engage bearings 26 carried by the respective outer arms of the plurality of arms 20.

The lower corners of the base member 10 are provided with vertical slots 28 so that the outer portions adjacent each slot may be turned upwardly to provide hook elements 30 that engage the web portion 32 of member 24, for holding and supporting the arms 20 in a raised position and at right angles to the base member 10.

The space between adjacent arms 20 is such that a pair of pants may be slipped therebetween so that the cuffs of the pants or trousers bear upon the upper edge of the arms 20. Obviously, dresses, skirts, ties and other like garments may also be quickly and readily inserted between adjacent arms in a convenient manner.

To collapse the device thus described, it is merely necessary to raise the arms 20 slightly and to disengage the member 24 from hook 30, whereby the arms and member 24 will be suspended in a vertically disposed position from pin 18, as shown best in dotted lines of Figure 2.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A garment hanger for receiving the cuffs of men's trousers comprising a substantially flat base member having upper and lower corners, spaced ears projecting from the upper corners of said base member, a shaft journaled for rotation on said ears, a plurality of arms having inner terminals fixed to said shaft, spacer blocks fixed between adjacent arms and to said shaft, said plurality of arms including a pair of outer arms,

a U-shaped brace member having a web and in-turned end portions, bearings carried by said outer arms adjacent the inner terminals thereof receiving the in-turned end portions of said brace member, and hooks struck outwardly from the lower corners of said base member for receiving the web of said brace member.

2. A garment hanger for receiving the cuffs of men's trousers comprising a substantially flat base plate having upper and lower corners, ears integrally formed with the upper corners of said plate and projecting laterally from the plate, a shaft carried by the ears and spaced from the plate, a plurality of arms pivoted on the shaft for vertical swinging movement, spacer blocks interposed between adjacent arms and received on said shaft, a substantially U-shaped brace having a web and in-turned terminals, said arms including a pair of outer arms, bearings carried by said outer arms adjacent the pivoted ends thereof receiving the in-turned terminals of said brace, said plate having a lower edge, a pair of substantially vertical slits provided in the lower edge of said

plate and adjacent the lower corners to provide a pair of corner strips, said strips being bent to form a pair of hooks for receiving the web of said brace when the arms are disposed perpendicular to said plate.

FREDERICK P. SCHROEDER.
